UNITED STATES PATENT OFFICE.

AUGUST J. WALTERS, OF MAPLE HEIGHTS, OHIO.

RECORD CABINET.

Application filed June 6, 1927. Serial No. 196,988.

The invention relates to record cabinets and has for its object to provide a simple and convenient device by means of which data of any kind can be permanently kept in a cabinet, even for a period of years if desired, and in such condition that the data can be referred to at any time.

For example, it will be found useful for keeping a permanent record of production, sales, receipts, shipments, or similar information, in such manner that the record, or any part thereof, cannot be removed or become lost or otherwise destroyed.

The invention comprises a paper strip or web mounted on reels in a casing, and passing across or behind an opening in the front of the casing. The web may be wound from one reel to the other, and the records can be written on the web, or, in the form shown, can be typed or written on a small paper or sticker which is stuck on the web and thereafter travels therewith and is wound upon one of the reels. A sticker may be applied each day, week, month, or other time interval, the web being moved up at each interval to receive a new sticker containing the records to be preserved. The cabinet will then contain permanent record according to the time intervals, and if desired the record can be turned back to show the same for any desired date.

The device also embodies various other features of importance or advantage, as will be apparent from the following description.

One form of the invention is illustrated in the accompanying drawings, in which Fig. 1 is a top plan view of the cabinet. Fig. 2 is a front elevation. Fig. 3 is a vertical section on line 3—3 of Fig. 1. Fig. 4 is a cross section on line 4—4 of Fig. 1. Fig. 5 is an enlarged detail of the operating and locking device. Fig. 6 is a section on the line 6—6 of Fig. 5. Fig. 7 is a detail of one of the locking devices. Fig. 8 is a section on the line 8—8 of Fig. 3. Fig. 9 is a top view of the parts shown in Fig. 8. Fig. 10 is a section on the line 10—10 of Fig. 3.

The casing 80 of the cabinet is properly shaped to contain the parts to be described, and it may be made of metal, and has a removable top 77 and a removable bottom 78. The front wall of the casing has a slot or opening 81 through which the web 75 is exposed, and adjacent the opening is a glass plate 52, under which may be placed a title

or list of items corresponding to the data to be recorded.

The paper strip or web 75 is attached at one end to a spool 40, as by a removable segment 56, and at the other end is attached to the spool 55 in a similar manner. The spool 40 is held between centering spindles 27 and 39, the former of which is mounted in a bearing in a plate 30, and the spindle 39 is mounted in a bearing in a plate 37, these plates extending across within the casing and being held in position by angle brackets 47 secured to the end walls of the casing. Similarly, the spool 55 is held between spindles 29 and 34 also mounted in bearings in said plates.

The intermediate operating shaft is mounted in the casing, and comprises rod sections 6 and 8 and a connecting sleeve section 7, the rod 6 having a crank 2 attached to the top thereof. The rods 6 and 8 are united to the sleeve 7 by pins 72 and 73 inserted through holes in the sleeve and the rods. The section 8 may be connected to a sprocket 10 connected by a belt 16 to the sprocket 35 on the spindle 34, or to a sprocket 14 connected by a belt 17 to a sprocket 44 on the spindle 39, the belt 17 passing over an idler 59 adjustable by means of a slot 76 in the bracket 82 supported by a plate 60 fixed to the plate 37.

The shaft 8 may be clutched to either the sprocket 10 or the sprocket 14 to wind the web in either direction, by shifting the shaft either up or down. When shifted down, a pin 69 will engage in a notch 69^a in the hub 10^a of the sprocket 10, this hub being mounted in a bearing in a plate 9 extending across the casing. When shifted up, a pin 74 on the shaft section 8 will engage in a notch 74^a in the hub 14^a of the sprocket 14, said sprocket being supported by a spacer 15 on the bottom of the casing. When one clutch pin is engaged the other is disengaged.

Spool flanges 23, 24, 25 and 46 are mounted on the respective spindles, to guide the web, and to prevent overrunning of the spools brake members are provided consisting of balls 33 pressed by springs 31 and held by thimbles 32 secured to the plate 30, the balls pressing against the flanges 23 and 24 to prevent spinning thereof in unwinding.

The shaft section 6 extends through a sleeve 18 fixed to the top of the casing and provided with upper and lower slots 66 and 110

65 and an intermediate slot 67, connected by a vertical passage, and a pin 50 may be shifted into any one of these slots, said pin projecting from a collar 90 held between collars 91 fixed to the shaft 6; and the pin adapted to be locked in any one of the slots by means of a lock 92 the loop of which may be passed through a hole in a lip 93 projecting from the sleeve 18, so that the pin 50 10 cannot be shifted from one slot to another, and consequently the shaft 6 cannot be raised or lowered until the lock is removed. To lock the shaft in neutral position, the shaft may be turned and lifted slightly until 15 the pin 50 swings into the opening between the two ears 93^a and 93^b and the loop of the lock 92 may be passed through the holes in these ears to prevent movement of the pin and shaft. Furthermore, to lock the 20 crank it is provided with a sliding pin 49 which may be raised or lowered to engage or disengage a series of holes 19 in the plate 98 on top of the casing 77, the pin being moved by a handle 70, and adapted to be locked 25 in position by lock X inserted through holes 95 in the handle and pin. When the pin is lowered into one of the holes 19 the crank cannot be turned.

For applying stickers to the web 75, at the 30 opening 81, I provide a gummed sticker tape 97 on which data may be written, and this is threaded through between the rollers 63 and 64 of a traveling frame 62 which has a guide bracket 96 slidable on a rod 61 fastened to the front of the casing by fixtures 71. The roller 63 is moistened, and after 35 the tape 95 is threaded between the rollers the frame 62 may be run up on the guide rod 61 and roller 64 will press the moistened 40 tape against the web 75, sticking the same thereon.

In the use of the device the web is wound up one way to expose successive portions thereof at the opening 81 and a sticker is 45 applied to each portion, this sticker containing the data to be preserved. At successive operations the web is wound up to preserve

the record in the cabinet. If it be desired to refer to an old record of any particular date, the operating shaft is shifted to reverse the web, which can then be unwound to the date desired, to show the record of that date. The locking devices prevent tampering with the record, and the whole forms a convenient device for preserving a record in a permanent form, superior to loose card or leaf records which may become lost or misplaced.

I claim:

1. The combination with a reel and web, 60 and a casing enclosing the same having an opening at which the web is exposed, of means to apply a sticker to the web at said opening.

2. The combination stated in claim 1, said means comprising a frame shiftable across 65 said opening and provided with a roller to press the sticker against the web.

3. The combination stated in claim 1, said means comprising a guide rod on the casing beside said opening, a frame slidable on the rod across said opening, and a roller carried by the frame to press the sticker 70 against the web.

4. The combination with a casing, and a 75 plurality of reels and a web therein, of an operating shaft, driving clutch connections between the shaft and the reels respectively, said shaft being shiftable lengthwise to engage either clutch, and a locking device to 80 hold the shaft in either position, said locking device including a sleeve having spaced slots, through which sleeve the shaft extends, and a pin operatively connected to the shaft and movable into any one of the slots.

5. The combination of a casing, a plurality of reels and a web therein, means to 85 operate the reels, and a brake device for each reel, comprising a spring-pressed ball resting against the reel.

In testimony whereof, I do affix my signature.

AUGUST J. WALTERS.
